UNITED STATES PATENT OFFICE

2,560,800

ELECTRICAL CIRCUIT BREAKER

Herbert W. Koch, Cicero, Ill., assignor to Western Electric Company, Incorporated, New York, N. Y., a corporation of New York

Application December 31, 1947, Serial No. 794,972

2 Claims. (Cl. 175—294)

1

This invention relates to electrical circuit breakers and more particularly to a protective circuit breaker for an electrical line.

It is an object of this invention to provide a new and efficient circuit breaker for electric lines.

In accordance with one embodiment of this invention an apparatus for protecting an electrical line against overloads and short circuits is provided with switching contacts for opening and closing the line, the contacts being held closed under normal conditions by a normally operated parallel relay connected across the load through the closed break contacts of a normally unoperated relay connected in series with the load. In case of an overload, the series relay operates to release the other relay thereby breaking the line, thus releasing the series relay and again operating the other relay to close the line. This cycle keeps repeating itself until the line is relieved of the overload. In case of a short circuit in the line, the shunt effect of the short around the parallel relay causes the current through the parallel relay to drop to immediately release the relay and open the line thus removing the direct shunt from across the parallel relay permitting it to reoperate, the cycle being repeated until the short circuit is removed.

A complete understanding of this invention will be had by referring to the following detailed description taken in conjunction with the single figure drawing in which one embodiment of the invention is illustrated by a circuit diagram.

As shown in the drawing, a circuit breaking apparatus comprising relays 10 and 11 is utilized to protect an electrical circuit comprising a source of electrical energy 12 connected to a load 13 through electrical lines 14 and 15.

The relay 10 which is normally unoperated comprises an operating coil 21 connected in the line 15 in series with the load 13 and a pair of normally closed break contacts 20. The relay 11 is normally operated and is provided with a pair of normally closed make contacts 22 and an operating coil 23 having one end connected to the line 14, the other end of the coil being normally connected to the line 15 through the closed contacts 20; thus while the relay 10 is connected in series with the load 13, the relay 11 is normally connected across the lines 14 and 15 and in parallel with the load 13.

The contacts 22 serve as a switch in the line 14 and operate to break the line circuit when the relay coil 23 is deenergized. Excessive arcing between the contacts 22 may be prevented by

2

connecting a resistor 24 across the contacts as shown in the drawing. A lamp 25 may be connected to the lines 14 and 15 in parallel with the load 13 to indicate the condition of the circuit.

5 The operating characteristics of the relay 11 are such that under normal load conditions the break contacts 20 remain closed due to the fact that the current through the operating coil 21 will be insufficient to operate the relay 10. However, if there is an increase in the load 13 beyond predetermined safe limits, the relay 10 will be operated by the increased current through its operating coil 21, thereby breaking the contacts 20 and releasing the relay 11. Upon release of 10 the relay 11, the contacts 22 are opened, and the direct line circuit 14 to the load 13 is broken. The resistor 24 remains in the circuit but its resistance should be high enough to limit the current below the value required to operate relay 10. 15 When the line circuit 14 is broken at opened contacts 22, the relay 10 is released to close contacts 20 thereby reoperating relay 11 and again closing the line at the contacts 22. This causes relay 10 to operate again thereby releasing relay 11 20 to again open the line at contacts 22. This cycle is repeated until the load 13 is reduced to normal, whereupon relay 10 will be unoperated and relay 11 will be operated to maintain the line circuits at contacts 22. While the line is intermittently 25 opened and closed at contacts 22 during the period of the overload, the normally lighted lamp 25 will flicker to provide a visible danger signal.

30 The design and the type of relays chosen are dependent upon the timing relation desired for a particular case. The timing relation may be such as to provide a short "on" time and a long "off" time during the overload or vice versa.

40 Preferably the relay 11 has a fast "release" time as compared to the "operate" time of the relay 10. A short circuit or a near short circuit in the load 13 will cause the relay 11 to release before the relay 10 can operate thereby breaking the line circuit at the contacts 22. This is due to the fact that the short circuit in the load forms a direct 45 shunt across the relay 11 and drops the current through the relay. Breaking of the line circuit at contacts 22 removes the direct shunt from across relay 11 thereby permitting it to reoperate to again close the line at contacts 22. This 50 cycle is repeated until the short circuit is removed, after which the line circuit to the load is restored. The indicator lamp 25 will flicker while the short circuit exists.

The average power consumed during an over-load when this circuit breaking apparatus is used

will be lower than that consumed by a conventional circuit breaker, especially if the "on" time of contacts 22 is a relatively short part of the time of the make and break cycle during the overload period. The apparatus described herein will, with a minimum of power drawn from the line, intermittently break an overload or shorted electrical power line until the line is relieved of the overload and then restore the line circuit when the overload or short circuit is removed.

It is to be understood that the above-described arrangements are simply illustrative of the application of the principles of the invention. Numerous other arrangements may be readily devised by those skilled in the art which will embody the principles of the invention and fall within the spirit and scope thereof.

What is claimed is:

1. A circuit breaking apparatus comprising a source of current, a load connected to said source, a normally unoperated first relay with normally closed break contacts, said relay having an operating coil connected in series with said source and said load and being unoperative under normal loads, a normally operated second relay having an operating time less than said first relay connected across said load through said break contacts, said second relay having normally closed make contacts and operable upon release to open and break the circuit between the source of current and the load, said second relay being de-energized before operation of said first relay when a short circuit occurs in said load so that increased protection is afforded under short circuit conditions.

2. A circuit breaking apparatus comprising a source of current, a load connected to said source, a normally unoperated first relay with normally closed break contacts, said relay having an operating coil connected in series with said source and said load and being unoperative under normal loads, a normally operated second relay having an operating time less than said first relay con-

nected across said load through said break contacts, said second relay having normally closed make contacts and intermittently operated upon release to open and break the circuit between the source of current and the load when the current to said load exceeds a predetermined value, said intermittent operation enabling said first and second relays to immediately resume normal operating conditions when the current falls below said predetermined value, said second relay being de-energized before operation of said first relay when a short circuit occurs in the load so that increased protection is afforded under short circuit conditions.
